UNITED STATES PATENT OFFICE.

OVILA W. BOYEA, OF BARRE, VERMONT.

AEROPLANE.

1,299,111.

Specification of Letters Patent.

Patented Apr. 1, 1919.

Application filed January 15, 1918. Serial No. 211,924.

To all whom it may concern:

Be it known that I, OVILA W. BOYEA, a citizen of the United States, and a resident of Barre, in the county of Washington and State of Vermont, have invented a new and Improved Aeroplane, of which the following is a full, clear, and exact description.

Among the principal objects which the present invention has in view are: to increase the propelling feature of the driving mechanism with which the aeroplane is provided; to increase the levitation of the aeroplane; to regulate the flight, and to check the flight of the aeroplane.

15

Drawings.

Figure 1 is a top plan view of an aeroplane constructed and arranged in accordance with the present invention;

20 Fig. 2 is a vertical longitudinal section thereof, the section being taken as on the line 2—2 in Fig. 1;

Fig. 3 is a horizontal section, the section being taken as on the line 3—3 in Fig. 2;

25 Fig. 4 is a front elevation of the aeroplane;

Fig. 5 is a vertical cross section, the section being taken as on the line 5—5 in Fig. 2.

30

Description.

As seen in the drawings, the car 10 is drawn to a point or sharp prow 11. The prow 11 forms a support for a U-shaped frame 12 and a central stanchion 13. The 35 stanchion 13, as seen best in Fig. 2, forms a central support for a tie brace 14, on which is mounted a bearing box 15 for the main driving shaft 16. The shaft 16 is extended lengthwise of the aeroplane in a line 40 parallel with the longitudinal axis thereof.

It is supported by a second U-shaped frame 17, best shown in Fig. 4 of the drawings, and by a cross brace 18 connected therewith. The driving shaft 16 is provided with a 45 mitered gear wheel 19.

At the opposite ends of the shaft 16, are mounted propellers 20 and 21. The propellers 20 and 21 are preferably of equal size and pitch. The shaft 16 is operatively connected with a motor 22, by means of a sprocket chain 23, said shaft being supported adjacent its rear end by a cross brace 24. The brace 24 is carried on stanchions 25, which support the deck 26.

The deck 27 and an overhang 28 meet at 55 the forward ends of the aeroplane to form a cutting edge 29, by which the air is divided, part to be lifted and part to be depressed. The deck 27 and overhang 28 have triangular receding sections 30 and 31. The 60 forward edges of the deck 27, overhang 28, and sections 30 and 31 converge, as shown best in Figs. 1 and 4 of the drawings. These planes form at the rear thereof, a space and chamber triangular in cross section. The 65 upper and lower decks are prevented from collapsing by thin braces 32.

At the rear of the extreme end of the chamber thus formed, the main carrying planes of the aeroplane are located. The 70 carrying planes referred to each comprise two sections, to wit, the solid section 33, and a rear section, embodying a series of closely-fitting slats 34. The slats 34 are pivotally mounted on rails 35, downwardly and rearwardly curved, as shown best in Fig. 2 of the drawings. The slats 34 are pivoted at the rear of each slat. All of the slats are connected by a framework 36 and a link 37, to a lever 38, the handle 39 whereof is adjacent the driver's seat 40.

As shown best in Figs. 3 and 5, a straight passageway is formed over the top of the fuselage of the machine and between the carrying planes 33 and sets of slats 34. It 85 is through this passageway that the propellers 20 and 21 operate.

In line with the above-mentioned passageway and adjacent the controlling rudders of the machine, are pivotally mounted vertical slats 41. The slats 41 are operatively connected by pivotally operating rods 42, the ends whereof are connected with bell crank levers 43 at opposite sides of the machine. The long ends of the levers 43 are 90 connected by means of rods 44, with operating levers 45. The levers 45, as seen best in Figs. 2 and 5 of the drawings, are disposed adjacent the driver's seat 40.

The slats 41 may be simultaneously or independently operated to open and close. When closed, the passageway above referred to as extending lengthwise of the machine, is virtually closed or an abutment is formed by which the air is pocketed to form a drag or anchor for the machine. It is obvious that if one set of slats 41 is permitted to remain open while the opposite set is closed,

the closed set will form a drag at one side of the vertical longitudinal plane of the machine, thereby operating as a rudder. In operating the machine, this aid is often taken advantage of.

At the rear of the slats 41, are disposed the horizontal rudder 46 and the climbing and diving rudders 47. As best shown in Fig. 2 of the drawings, there are two rudders 47. The rudder 46 has cutaway or inclined end edges 48 for permitting the lift and depression of the rudders 47. The rudders 46 and 47 are operated by any of the conventional forms of mechanisms furnished.

The wheel 19 on the shaft 16 is operatively engaged with a gear wheel 49. The gear wheel 49 is fixedly mounted on a shaft 50, which shaft extends transverse the aeroplane. As seen best in Figs. 3 and 5, the shaft 50 has permanently mounted thereon two propellers. As seen best in Fig. 2, the propellers are provided with cupped blades 51. The shaft 50 is mounted in bearings which hold the shaft at approximately the level of the lower edge of the overhang 28, which serves to protect or shelter the upper portions of said propellers, or to shelter the blades 51 when extended above the horizontal center of the shaft 50.

In consequence of this arrangement, the propellers and blades 51 thereof serve to press the air with which they are brought into contact, downward and rearward, thus forming auxiliary levitating and propelling means.

To operate an aeroplane when constructed and arranged in accordance with the present invention, the motor 22 is started and the power generated thereby is transmitted by means of the chain 23, to the shaft 16. The propellers 20 and 21 are rotated with equal effect to propel the machine in a forward direction. Through the intermediary of the gear wheels 19 and 49, the shaft 50 with the propellers at the lateral extremes thereof, is rotated. The operation of the blades 51 of the propellers, as above stated, is to grip the air and press the same backward with the resulting effect that the aeroplane is moved forward, the operation being in unison with the operation of the propellers 20 and 21. In other words, the power mechanism with which the aeroplane is provided is distributed at four points, thereby steady- ing the operation of the driving mechanism and the action of the aeroplane. As the operation of the blades 51 of the propellers mounted on the shaft 50, is to depress the air, the blades serve to stabilize the action of the aeroplane in its flight.

During the flight of the machine, it will be observed that when the same is held steady in its forward course, the wedge- shaped construction produced by the deck

27, overhang 28, and sections 30 and 31, assists in steadyng the flight of the machine as the pressures produced on the inclined surfaces of the said members are equalized. If, however, the rudders 47 are deflected to change the angle of flight, it will be seen that the angle of incidence or air pressure will be increased on the upper or lower decks in correspondence with the pitch of the aeroplane to climb or dive. Also it will be seen that the wedge-shape construction automatically adjusts itself to the new direction of flight, and as soon as the same becomes established, assists in stabilizing the direction of flight.

The normal levitation of the aeroplane is supported by the operation of the blades 51 and the depressed sections formed by the slats 34 at the rear of the slat sections 33.

It will be noted that as the air is delivered rearwardly from the blades 51, it impinges upon the slats 34, which, if closed, form sections that exert a levitating or upward gliding effect, thereby assisting in lifting the aeroplane.

It is obvious that if the aviator desires to alter the lifting power of the sections formed by the slats 34, he accomplishes this by manipulating the levers 39 to open and close the said slats. By opening the said slats, the air pressure on the sections composed thereby, is relieved.

During the normal flight of the aeroplane, the slats 41 at the rear of the machine are maintained open as shown in the drawings.

If it is desired to arrest the flight of the machine as when making a landing, the aviator by operating the levers 45, closes the slats 41, with the effect of producing a solid wall perpendicular to the line of flight, which serves as a drag on the air. It will be noted that the action of the construction formed by the slats 47 may be modified by completely or partially closing said slats.

While the operation of the slats 41 and the sections formed thereby is normally employed to assist in landing, said slats may be employed for checking the headway of a machine in midair for avoiding collision or for maneuvering as when employed in military service. Further, the slats may be used as a help to sustain the machine or diminish the rate of descent thereof as when falling.

Claims.

1. An aeroplane comprising a plurality of carrying planes, said planes having rearwardly-depressed inclined sections; a protective structure disposed above said inclined sections; and means for varying the resistance of said inclined sections, said means embodying a plurality of slats pivotally mounted for closing one upon the other to produce a solid wall, and means manually controlled for opening said slats.

2. An aeroplane comprising a plurality of carrying planes, said planes having rearwardly-depressed inclined sections; a protective structure disposed above said inclined sections; and means for varying the resistance of said inclined sections, said means embodying a plurality of slats piv-
5 otally mounted for closing one upon the other to produce a solid wall, and a controlling mechanism operated manually and having a hand lever contiguous to the seat of the driver of the aeroplane for rocking said slats on their pivots.

OVILA W. BOYEA.
